BURGLAR-ALARM WALL CONSTRUCTION

Robert S. Kahn, Brooklyn, N. Y.

Application February 11, 1937, Serial No. 125,217

1 Claim. (Cl. 109—42)

One object of this invention is the provision of wall sections, such as are commonly used in covering the skeletal frame of the walls and partitions of houses and other buildings, with means 5 mounted integrally in the sections so that the completed wall will serve, in combination with an electrical circuit, as the means for setting off a burglar alarm if a hole is dug through the wall for the entry of a person's body there- 10 through.

The invention is illustrated and described below to set forth one way in which the above object may be attained, but it may also be attained in other ways, as will be observed below.

15 The above and other objects will become apparent in the description below, in which characters of reference refer to like-named parts in the accompanying drawing.

Referring briefly to the drawing, Figure 1 is a 20 diagrammatic view illustrating a portion of a wall formed of sections constructed in accordance with this invention, together with a wiring diagram.

Figure 2 is a fragmentary perspective view, 25 partly in section, of a wall section.

Figure 3 is a perspective view of the switch for setting the alarm circuit.

Referring in detail to the drawing, the numeral 10 indicates a wall board or section formed 30 of any material of which such sections are commonly made. On each end of the section 10, a metal strip 11 is imbedded with a peripheral projection 12 of the section 10 surrounding the strip 11. A wire 13 of small diameter and light 35 weight, such as might be readily severed if a small amount of pressure is applied thereto, is set integrally and concealed within the section 10, and possesses a series of spaced-apart parallel loops 14. The distance between the loops 14 40 is not over approximately five or six inches, so that this distance would be insufficient to permit a person's body to pass between adjacent loops. One end 15 of the wire 13 is attached in any desirable manner to the strip 11 on one end of 45 the section 10, and the other end 16 of the wire 13 is similarly secured to the strip 11 at the opposite end of the section 10. In covering the wall skeleton with the sections 10, the latter are set end to end with the strips 11 of each section 50 contacting with the strips 11 of adjacent sections. A lead wire 17 is secured in any desirable manner to the strip 11 which lies at the end of a series of such sections 10, and a similar wire 18 is attached to the strip 11 at the opposite end 55 of such a series. The wire 17 leads through a

relay 19 to a battery or other source of electric supply 20. From the battery 20, a wire 21 joins a wire 22 which leads to one pole 23 of a switch 24. The directly opposite pole 25 of the switch 24 has the lead 18 secured thereto. The wire 22 is continued beyond the lead 21 to the armature 26 of the relay 19. The relay contact 27 leads through a wire 28 to an alarm 29, and the wire 30 connects the other side of the alarm 29 with the pole 31 of the switch 24. Finally, a 10 wire 32 joins the pole 33 of the switch 24 with the battery 20 on the same side as the wire 17.

The switch 24 comprises a yoke having its blades or arms 34 and 35 separated by an insulated block 36, and a pivoted handle 37 rigid 15 with the yoke.

As shown in the wiring diagram of Figure 1, the circuit through the wire 17, the strips 11, the looped wires 13, and the wire 18 is open, that is, the alarm circuit is open. In setting 20 the alarm circuit so that it will be actuated in the event that any portion of any of the wires 13 is severed, the switch 24 is closed. When the latter is done, it is desirable that the circuit through the relay 19 is closed first so as to prevent sounding of the alarm at that instant. This is accomplished by having the poles 23 and 25 raised higher above the base 38 than the poles 31 and 33, so that the arm 34 of the switch 24 25 will bridge the poles 23 and 25 before the arm 30 35 bridges the poles 31 and 33. At the instant of contact of the arm 34 with the poles 23 and 25, current flows from the battery 20 through lead 17, relay 19, to the topmost strip 11, down through the series of wires 13, out at the bottom 35 strip 11, through lead 18, pole 25, arm 34, pole 23, lead 22, and lead 21. Thus, the energized relay 19 attracts the armature 26 and separates the latter from its contact 27. As the arm 35 of the switch 24 descends into contact with its poles 40 31 and 33, the circuit through the alarm 29 and battery 20 is closed at every point excepting at that between the armature 26 and contact 27. If now the wall in which the sections 10 are 45 mounted is broken through by chiseling or in any other manner so that any of the wires 13 are severed at any point, the circuit through the relay 19 is instantly opened so that the armature 26 is released and swings back to contact with the contact 27, and thus closes the battery circuit 50 through the alarm, causing the latter to sound. If a series of vertical sections 10 are provided side by side to cover an entire wall, a single 55 alarm circuit such as that shown in Figure 1 may be used with a plurality of relay circuits

with each of the latter connected in one vertical series of sections 10.

- As set forth above, the construction embodies the sounding of an alarm upon the severance 5 of one of the wires 13. A modified construction might be used, however, in which it will not be necessary to actually sever a wire in the wall section, but simply to cause opposite sides of any loop 14 to be brought into mutual contact. 10 In such case, the relay would be of such design that upon the reduction of the total resistance of the series of wires 13 between the strips at the top and bottom of such a vertical series of sections 10, the relay will receive sufficient additional current to attract its armature and thus 15 close an alarm circuit. However, it is believed that the construction illustrated and described is the most practical, as by the provision of relatively soft thin and easily broken wires 13, 20 it will be impossible for any person to chisel a hole through a wall without severing such a wire.

By the term "wall" used in the above description, is implied also "ceiling" and "floor", as similar sections 10 may be applied to ceilings

and floors in the same manner and for the same purpose.

A wall having sections such as those above described mounted therein, could be used as a radio aerial by connecting one end of the wire 5 13 of any section with the antenna post of a radio.

Obviously, modifications in form and structure may be made without departing from the spirit and scope of the invention.

I claim:

A burglar alarm wall construction consisting of the provision of a plurality of wall sections adapted to be mounted end to end to cover a length of wall, each of said sections comprising a substantially rectangular body formed of any desired building material, metallic strips imbedded in opposite edges of each section, a looped wire imbedded in said body and having its ends secured to the said strips at the opposite edges 15 of said body, the loops of said wire being relatively close together, said wire being formed of a relatively fragile material.
